(57) **CLAIM**

The ornamental design for an autoinjector with removable cap, as shown and described.

DESCRIPTION

FIG. 1 is a perspective view showing a new design for an autoinjector with a removable cap, showing the removable cap disposed on the autoinjector;

FIG. 2 is a front view of the autoinjector of FIG. 1;

FIG. 3 is a rear view of the autoinjector with removable cap of FIG. 1;

FIG. 4 is a left-side view of the autoinjector with removable cap of FIG. 1;

FIG. 5 is a right-side view of the autoinjector with removable cap of FIG. 1;

FIG. 6 is a top view of the autoinjector with removable cap of FIG. 1;

FIG. 7 is a bottom view of the autoinjector with removable cap of FIG. 1; and,

FIG. 8 is a perspective view showing the autoinjector drug with removable cap of FIGS. 1-7 with the removable cap removed.

The autoinjector is shown with symbolic breaks in its length. The appearance of any portion of the article between the break lines forms no part of the claimed design.

The dashed lines immediately adjacent to the shaded areas in the figures represent the boundaries of the claimed design. The dashed lines in the figures illustrate the portions of the design that form no part of the claimed design. None of the broken lines form any part of the claimed design.
